Primary Examiner — Calvin E Vansant*Assistant Examiner* — Mark T. Philippss(74) *Attorney, Agent, or Firm* — Cislo & Thomas, LLP(57) **CLAIM**

The ornamental design for a centrifugal pump, as shown and described.

DESCRIPTION

FIG. 1 is a rear perspective view of my centrifugal pump; FIG. 2 is a rear view thereof;

FIG. 3 is a front view thereof;

FIG. 4 is a right side view thereof;

FIG. 5 is a left side view thereof;

FIG. 6 is a top plan view thereof; and,

FIG. 7 is a bottom plan view thereof.

The broken lines shown in the drawings illustrate portions of my centrifugal pump that form no part of the claimed design.

1 Claim, 7 Drawing Sheets# US D986,289 S
